UNITED STATES PATENT OFFICE

MORRIS STORCH AND ISAAC FRANK, OF BROOKLYN, NEW YORK

BRUSH ATTACHMENT FOR AUTOMOBILES

Application filed November 23, 1928. Serial No. 321,500.

The present invention relates to improvements in brushing or sweeping devices and has reference more particularly to an attachment for a motor vehicle equipped with pneumatic tires, the primary object of the invention residing in the provision of a brushing attachment for clearing the path of the front wheel of the vehicle of and removing therefrom, broken glass, nails, tacks or any other 10 obstructions that may be encountered and which would puncture or otherwise damage the pneumatic tires of the front wheels of a vehicle.

One of the important objects of the invention resides in the provisions of a brush attachment that can be readily and easily installed on an automobile without necessitating any material alterations of the parts with which the brushing attachment is associated, 20 the device being at all times positive and efficient in carrying out the purposes for which it is desired.

A further object is to provide a brush attachment for vehicles of the above mentioned 25 character wherein means is provided for adjusting the height of the brushing or sweeping member with respect to the ground, additional means being provided to permit swinging movement of the brush head when the 30 same strikes a large obstruction so that the brush head may pass over said obstruction without causing damage to the brush attachment.

Still a further object is to provide a brush 35 attachment wherein the parts are so arranged as to deflect the broken glass, nails or the like to one side of the road.

Still a further object is to provide a brush head attachment of the above mentioned 40 character which is simple in construction, inexpensive, strong and durable and further well adapted to the purposes for which it is designed.

Other objects and advantages will become 45 apparent during the course of the following description.

In the accompanying drawing, forming a 50 part of this specification, and in which like numerals indicate like parts throughout the same:

Figure 1 represents a front elevation of the brush attachment embodying our invention showing the manner in which the same is mounted on an automobile.

Figure 2 is a side elevation showing front 55 and rear brush units,

Figure 3 is a vertical sectional view through one of the brush units,

Figure 4 is a top plan view for more clearly disclosing the attaching means for a brush 60 unit,

Figure 5 is a sectional view taken approximately on the line 5-5 of Figure 4 looking in the direction of the arrows,

Figure 6 is a sectional view taken on the 65 line 6-6 of Figure 3,

Figure 7 is a detail view showing the means for adjustably securing the lower frame in the stationary upper frame and,

Figure 8 is a detail perspective view of the 70 removable brush.

In the drawings wherein for the purpose of illustration is shown the preferred embodiment of our invention, the numeral 1 designates a substantially rectangular shaped 75 channeled frame that is curved as suggested in Figure 6.

This frame is disposed in front of as well as directly rearwardly of each of the front wheels A of an automobile. The supporting 80 means for the frame disposed forwardly of each front wheel includes the upper and lower rods 2 and 3 respectively. The forward ends of these rods are secured to the inner side portion of the frame 1 while the rear end 85 of said rod has connection with a vertical plate 4 that is disposed against the front axle B in the manner as clearly suggested in Figures 4 and 5.

A similar plate 5 is disposed against the 90 rear side of the front axle and suitable securing bolts 6 extend through the upper and lower ends of the aligned plates 4 and 5 for engagement with the upper and bottom faces of the front axle to rigidly secure the plates in 95 position as also shown in Figure 5.

Additional rods 7 extend from the stationary frame in a rearward direction and the rear ends of these rods are connected to a vertical cross piece 8 that extend between the 100

intermediate portions of the rods 2 and 3 and brace rods 9 extend laterally from the cross piece 8 to a plate 10 that is disposed against the front side of the front axle B inwardly of the plate 4.

5 A plate 11 is secured against the rear side of the front axle B in alignment with the plate 10 by bolts 12.

10 The stationary frame of the rear brush unit is supported in a similar manner. The rods that extend from the plate 5 to the frame of the rear brush units are shown at 13 and 14 respectively while the brace rods that extend from the plate 11 are indicated at 15.

15 Upon referring to Figure 7 it will be observed that the frame 1 is provided in its front side with a screen 16, the edges of the screen being disposed within suitable channels formed in the respective sides of the frame.

20 Each brush unit includes a slidable lower frame 17 which is also slightly curved and this frame 17 is slidable between the channeled sides of the stationary upper frame 1 through the bottom of the stationary frame.

25 A handle 18 extends across the rear portion of the sliding frame 17 for manually raising and lowering the frame and for the purpose of holding the slidable frame in any vertically adjusted position with respect to the stationary upper frame 1, we provide the set screws 19 that extend through the opposite sides of the stationary frame 1 and engage with the adjacent side edges of the slid-
30 able frame in the manner as also clearly disclosed in Figure 7.

35 The sliding frame 17 is covered with a screen 20. Each brush unit further includes a brush head 21 that is formed at its upper edge with the longitudinally extending channel 22 in which is secured the lower edge of a relatively stiff piece of rubber 23, the upper edge of this strip of rubber being attached to the lower edge of the sliding frame 17 by suitable clamping plates or strips 24 as shown in Figure 3.

40 The purpose of the rubber connecting strip 23 between the frame 17 and the brush head 21 will be hereinafter more fully described.

45 The lower edge of the brush head 21 is also formed with a longitudinally extending channel denoted by the reference character 25 for receiving a removable brush element shown generally at 26 in Figure 8.

50 This brush element comprises a channel shaped housing 27 that is adapted to be detachably secured in the channel 25 by any appropriate fastening means and the bristles 28 are secured in the housing 27 in any appropriate manner.

55 A metallic plate 29 extends downwardly from the rear side of the housing 27, the lower edge of this plate terminating above the ground engaging portions of the bristles 28.

When the brush units are positioned in front of and directly behind the front wheels of the automobile, the lower frame 17 is properly adjusted so that the bristles 28 engage the ground, it will be readily apparent that the bristles of the brush and the brushes will sweep away to one side any obstacles such as pieces of broken glass, nails, tacks and other sharp elements from the path of the wheels so that such elements cannot come in contact with the pneumatic tire and puncture or otherwise injure the same. 70

75 Should the brush units strike a large obstruction, the rubber strip 23 will permit the brush head to pass over said obstructions without breaking the brush heads or otherwise rendering the brush units impractical for further use.

80 The brush units are so arranged as not to impede the movement of the wheels over the road and furthermore the brush units may be readily and easily attached in proper position on the automobile without necessitating any alterations.

85 Furthermore the brush attachment will at all times be positive and efficient in carrying out the purpose for which it is designed and due to its simplicity the same can be manufactured at a very low cost and yet be strong and durable. 90

95 Should the bristles 28 wear away so as to render the brush inefficient in its operation, the brush may be readily and easily removed and replaced with a new one.

100 While we have shown the preferred embodiment of our invention, it is to be understood that various changes in the size, shape and arrangement of parts may be resorted to without departing from the spirit of the invention and the scope of the appended claims. 105

Having thus described our invention, what we claim as new is:

1. In a brush attachment for automobiles, a vertical member for disposition in front of each of the front wheels of the automobile, supporting means for said member, an additional member having its upper portion slidably associated with the stationary first mentioned member, means for adjustably securing the movable member with respect to the stationary member, a brush for engagement with the ground, and a flexible connection between the brush and the lower edge of the slidable member, said flexible connection comprising a strip of stiff rubber secured at its lower end to the head of the brush, the upper edge of the strip of rubber being secured to the lower edge of the slidable member. 110

115 2. In a brush attachment for automobiles, a vertically disposed channeled frame for arrangement in front of each of the front wheels of an automobile, supporting means therefor, a screen mounted in the stationary frame, an additional frame slidably mounted in the channeled frame, a screen carried by the 120

125

130

slidable frame, means for adjustably securing the slidable frame in any vertically adjusted position, a brush for engagement with the ground, and resilient means interconnecting the brush and the lower edge of the slidable frame.

3. In a brush attachment for automobiles, a vertically disposed channeled frame for arrangement in front of each of the front wheels of an automobile, supporting means therefor, a screen mounted in the stationary frame, an additional frame slidably mounted in the channeled frame, a screen carried by the slidable frame, means for adjustably securing the slidable frame in any vertically adjusted position, a brush for engagement with the ground, and a strip of stiff rubber secured at its lower edge to the head of the brush, the upper edge of the strip of rubber being secured to the lower edge of the slidable frame.

In testimony whereof we affix our signatures.

MORRIS STORCH.
ISAAC FRANK.
